UNITED STATES PATENT OFFICE.

NEHEMIAH T. FOLSOM, OF BOSTON, MASSACHUSETTS, ASSIGNOR TO JOHN S. FOLSOM, OF SAME PLACE.

THILL-LUG.

SPECIFICATION forming part of Letters Patent No. 254,763, dated March 7, 1882.

Application filed September 5, 1881. (No model.)

To all whom it may concern:

Be it known that I, NEHEMIAH T. FOLSOM, of Boston, in the county of Suffolk and State of Massachusetts, have invented certain Improvements in Thill-Lugs, of which the following is a specification.

This invention consists of a novel thill-lug, constructed substantially as I will hereinafter describe and claim.

10 In the accompanying drawings, Figure 1 represents a side elevation of a thill-lug embodying my invention. Fig. 2 represents an edge view of the same. Fig. 3 represents a section on line *x x*, Fig. 2.

15 The same letters indicate the same parts in all the figures.

In the drawings, *a* represents a metal thill-lug, having in its upper end a recess, *a'*, adapted to receive the ends of a leather loop, *b*, the 20 bight of which loop holds the cross-bar of the buckle *c*. The loop *b* is secured to the lug *a* by screws *d d*, which press a metallic plate, *e*, against the ends of the loop, said ends being interposed between the plate *e* and the recess 25 *a'*. The loop *b* can be readily removed by withdrawing the screws *d d*.

If desired, the plate *e* may also serve to secure a loop-strap, *f*, to the lug, as shown, one side of said loop-strap being interposed between 30 the plate *e* and the lug.

It will be seen that my invention enables a harness-maker to readily apply to a metallic

lug a buckle of any desired size and width, so that the lug can be readily applied to a saddle-strap of any desired width without requiring alteration of the strap. 35

My present invention is an improvement on the lug described in Letters Patent of the United States issued to me January 18, 1881, No. 236,703, the loop *b* taking the place of the 40 rigid socket formed in said patented lug to receive the cross-bar of the buckle, said loop giving the lug a neat appearance and enabling different sizes of buckles to be used with the same lug. The loop also prevents the wear to 45 the cross-bar of the buckle which the aforesaid rigid socket causes.

The loop *b* may, if desired, be made of any suitable material other than leather.

I claim—

The combination of the thill-lug having the recess *a'* in its upper end, the leather loop holding the buckle in its bight, the clamping-plate *e*, operating to clamp the ends of the loop in the recess of the lug, and the screws *d d*, substantially as described. 55

In testimony whereof I have signed my name to this specification, in the presence of two subscribing witnesses, this 31st day of August, A. D. 1881.

NEHEMIAH T. FOLSOM.
